WINDOW AND DOOR ADJUSTING AND HOLDING MECHANISM

John G. Shodron, John B. Olson, and Carl S. Wandschneider, Fort Atkinson, Wis., assignors to James Manufacturing Company, Fort Atkinson, Wis.

Application April 28, 1930. Serial No. 447,865

6 Claims. (Cl. 268—111)

Our invention relates to improvements in window and door adjusting and holding mechanism of the general type disclosed in a co-pending application, filed by John G. Shodron, Serial No. 5 344,641, filed March 6, 1929.

Objects of this invention are to provide improved means for utilizing crank operated connections for opening windows or doors, particularly windows or doors which are hinged along their upper margins and opened by swinging them to oblique positions with reference to the relatively fixed frame or wall of the building; also, to provide means for locking or securely holding the closure (door or window) in various open positions, and in the closed position; also, to provide means for simultaneously actuating a door or window by pressure applied adjacent to both side margins and securely holding it in the adjusted position by means of the actuating connections, such connections being simultaneously operable from a single crank or actuating member located either centrally or at one side of the opening.

In the drawings:

25 Figure 1 is an elevation of a swinging window designed particularly for use in the arched wall or roof of a building, and to which our invention has been applied.

Figure 2 is a sectional view of the same, drawn generally to line 2—2 of Figure 1.

Figure 3 is a view similar to Figure 2 showing modification.

Figure 4 is a fragmentary elevational view of the operating crank and associated parts shown in Figure 3.

Figures 5 and 6 are detail sectional views drawn generally to lines 5—5 and 6—6, respectively, of Fig. 4.

Figure 7 is a detail view of the adjustable connection between the crank and one of the rods connecting it with the window frame, a fragment of the connecting rod being illustrated.

Like parts are identified by the same reference characters throughout the several views.

45 In Figures 1 and 2, a window is illustrated which has a metal sash 10, applied to a window frame 11, mounted in a window opening formed in an arched wall 12, the upper rail of the window sash being connected to the frame by hinges 13. The 50 lower rail 14 will, for convenience, be termed the swinging margin of the sash.

A set of cranks 15 are connected to the window sill 16 by brackets 17, the cranks being pivoted to the brackets at 18. The two cranks illustrated 55 are connected with each other by a bar 19 which

is formed of resilient material. The ends of this bar are preferably elbowed and riveted to the cranks in reinforcing relation thereto. The extremities of the elbowed arms 20 being preferably apertured to receive the pivot pins 18.

Near their outer ends the cranks 15 are provided with brackets 22, U-shaped brackets being preferably employed, and provided with threaded apertures to receive the threaded ends of connecting rods 23. The brackets 22 are swivelled to the cranks, the central portion of each bracket being connected with its associated crank by a rivet or bolt 25, upon or with which the bracket may rotate.

The connecting rods 23 have elbowed ends 28 which extend through apertured ears 29, to which they are secured by cross pins or cotter pins 30. These ears 29 are connected with the sash frame in any suitable manner. It will be observed that by swinging either of the cranks 15, motion will be transmitted to the other through cross bar 19, and through the connecting rods 23 to swing the window sash upon its hinges. Cranking is avoided by the swivel connection between the brackets 22 and the cranks, and the pivoted connection of the connecting rods with the window sash.

In order that the sash may be locked in various positions of adjustment, we provide the window sill 16 with a toothed sector bracket 32, so located that its arcuate toothed portion will be in the normal path of the central portion of the cross bar 19 when said bar swings in association with the cranks. The spacing between the teeth 33 of the sector is such that the bar 19 will be received between the teeth, and the bar is preferably rectangular in cross section and of a width to snugly fit between the teeth 33. When the bar is in position between two teeth 33 of the sector, the sash will, of course, be securely locked against movement upon its hinges, and both side margins will be held with equal security against movement under wind pressure or any other force that may be exerted against the sash.

But when it is desired to change the adjustment of the sash, the engaging portion of the bar 19 may be sprung outwardly to a sufficient extent to release it from between the teeth 33, whereupon the bar may be raised or lowered and its motion transmitted to the cranks to open or close the window, or adjust it to a different open position. The bar 19 has sufficient resilient tension so that, when released, it will spring into sector engaging position if in registry with one of the notches between the teeth 33. If the bar should be carelessly left in engagement with one of the

teeth it will automatically engage in an adjacent notch as soon as the window commences to move under pressure of the wind or otherwise.

In Figures 3 to 7, inclusive, we have illustrated 5 a modified form of construction in which parts similar to those illustrated in Figures 1 and 2 are identified by the same reference characters with the letter *a* added. In these views the window frame and sash are substantially like 10 those disclosed in Figures 1 and 2, and no further description, thereof, will be necessary. The cranks 15*a* are pivoted to brackets 17*a* by the pivot pins or bolts 18*a* in a manner similar to that disclosed in Figures 1 and 2, but one of the 15 brackets 17*a* is provided with a toothed sector 32*a*, and the associated crank has an arm 40 to which a locking dog 41 is pivotally secured at 42. The locking dog 41 is of bell crank type with one arm 15 disposed for engagement between teeth 33*a* of 20 the sector 32*a*. The other arm of the dog extends over the crank arm 40 and is normally in spaced relation thereto, with an interposed spring 45, the ends of which are engaged with seating studs 46 and 47, carried by the dog and the arm 40, respectively. This arm 40 constitutes a convenient 25 means for connecting the cross bar 19*a*, through which motion is transmitted to the crank 15*a* at the opposite side of the window casing. The arms 43 of the locking dogs swing into locking 30 relation to the sector 32*a* with their intermediate portions between a pair of ears 49, carried by the associated crank 15*a*. These ears relieve the arms 43 and pivot pin 42 from excessive 35 strains which would otherwise be exerted by the wind when the window is held in its open or partially open position.

The connecting rods 23*a* may be secured to the window sash in the same manner as described 40 with reference to Figures 1 and 2. They may be secured to the crank 15*a* by a coupling 22*a* connected with the crank by a pivot pin or bolt 25*a*, the connecting rod being screwed into the coupling 22*a*. The latter is suitably socketed to receive it, as clearly shown in Figure 7.

45 In this modified form of construction, the toothed sector 32*a* will be located in association with one of the crank arms, and will, of course, be omitted from the bracket 17*a* associated with the other crank arm. Also, only one of the 50 cranks 15*a* will be provided with a locking dog or pawl 41.

We claim:

1. The combination with a swinging closure of window or door type, of a relatively fixed support, 55 a set of cranks pivoted thereto and respectively linked to the middle portions of the sides of the closure a resilient cross bar connecting, said cranks with each other for simultaneous operation, a toothed sector secured to the frame opposite the middle portion of said bar and adapted to normally receive the bar between its teeth for locking the cranks in various positions of adjustment to hold the closure in corresponding positions of open or closed adjustment.
- 60 2. The combination with a swinging closure of window or door type, of a relatively fixed support, a set of cranks pivoted thereto, linkage between the cranks and the sides of the closure brackets secured to the cranks in threaded engagement with said linkage to permit adjustment

of the latter therein, a bar connecting the cranks and means connected with the fixed support for engaging the bar in the various positions to which it may be swung by means of the cranks.

3. The combination with a swinging closure of window or door type, of a relatively fixed support, a set of cranks pivoted thereto, adjustable linkage between the cranks and the sides of the closure, a bar connecting the cranks and having a resiliently yielding portion, and an arcuately curved toothed sector connected with the support and disposed with its teeth in position for engagement with the resiliently yielding portion of the bar when the yielding portion of such bar is in normal position, said portion of the bar being manually retractile under pressure to release it from said teeth preparatory to re-adjustment of the cranks.

4. The combination with a swinging closure of window or door type, of a relatively fixed support, a set of cranks pivoted thereto and linked to the respective sides of the closure, a cross bar connecting said cranks and adapted to serve as a handle to operate the latter, a relatively fixed toothed sector associated with one of the cranks, a dog pivotally associated with the cross bar and adapted to be engaged between the teeth of said sector, said dog having an operating handle extending along the cross bar to be gripped for dog retraction when the cross bar is being used as a handle to operate the cranks, and a spring for normally urging the dog to sector engaging position.

5. The combination with a swinging closure of window or door type, of a relatively fixed support, 110 a set of cranks pivoted thereto and linked to the respective sides of the closure, a cross bar connecting said cranks and adapted to serve as a handle to operate the latter, a relatively fixed toothed sector associated with one of the cranks, 115 a dog pivotally associated with the cross bar and adapted to be engaged between the teeth of said sector, said dog having an operating handle extending along the cross bar to be gripped for dog retraction when the cross bar is being used as a handle to operate the cranks, and a spring for normally urging the dog to sector engaging position.

6. The combination with a swinging closure of window or door type, of a frame to which one margin of the closure is connected for pivotal swinging movements, a relatively fixed support at the side of the frame opposite said pivotal connection, a set of cranks pivoted to the support, adjustable linkage between the cranks and the sides of the closure, including members adapted to swing downwardly with the cranks to a closing position below the axial line about which the cranks swing, a locking device adapted to hold the cranks in various positions of adjustment, an operating bar connecting the cranks for simultaneous movement, and means whereby the locking dog may be retracted by the hand of the operator which grasps the operating bar.
